CLAIM

The ornamental design for a light bulb, as shown and described.

DESCRIPTION

FIG. 1 is a front, right side perspective view of a light bulb, showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is an enlarged top plan view thereof;

FIG. 7 is an enlarged bottom plan view thereof; and,

FIG. 8 is a bottom side perspective view thereof.

The broken lines in the drawings depict portions of the light bulb that form no part of the claimed design.

1 Claim, 8 Drawing Sheets
